FRED SCHULTZ, OF CINCINNATI, OHIO, ASSIGNOR TO THE LOCKWOOD MANUFACTURING COMPANY, OF CINCINNATI, OHIO, A CORPORATION OF OHIO

PAN CONNECTING AND REINFORCING STRIP

Application filed November 20, 1928. Serial No. 320,704.

This invention relates to a connecting strip or rail for use with multiple baking pans.

An object of the invention is to provide such a strip the exterior surface and adjacent edges of which are smooth and free from all grease and dirt-catching apertures, rivet heads, lugs or the like.

Another object is to provide a connecting strip which likewise strengthens and protects exposed surfaces of the pans in a baking unit.

Another object is to provide a bumper to protect and strengthen the top edges of the pans.

15 Another object is to provide a strip of the class described in which the means used to fasten the strip to the pans, are protected from contact with other objects whereby loosening of such means would result.

20 Another object is to provide a strip of the class described which presents no sharp points injurious to the hands and clothing of workmen using the pans.

These objects are attained by the means 25 described herein and set forth in the accompanying drawings, in which:

Fig. 1 is a side elevational view of a baking unit comprising a strip of the present invention, parts being broken away.

30 Fig. 2 is a view on line 2—2 of Fig. 1.

Fig. 3 is a detail view showing a fastening means for securing the strip to the pans, parts of the strip being broken away.

One of the customary methods of forming 35 a baking pan is to turn up parallel portions of a stamped piece of suitable sheet metal, there being two turned-up end portions and two turned-up side portions. Extensions of the side portions are folded at right angles 40 against the outer faces of the end portions, and secured in that position, thus forming closed corners on the pan. The top edges of the pan are then suitably finished off, 45 frequently by rolling the edges outwardly upon a wire or other strengthening piece which continues around the four edges of the pan.

A number of pans thus fashioned are then 50 connected together to form a baking unit,

and it is with this step that the present invention is concerned.

Heretofore, the usual method of forming a unit has been to bind the pans together by securing single strips of metal along the 55 outer end faces of a number of pans, one strip to each side of the unit. The lugs or rivets used to secure these strips to the pans present either depressions or studs along the strip, into or around which dirt and grease 60 can collect, a most undesirable feature where the most sanitary conditions are required. Moreover, the lugs and studs are exposed and become loosened by contact with other objects, and are also a source of trouble in 65 that they tend to scratch the hands and catch gloves or clothing of persons using the pans.

The present invention overcomes these disadvantages by providing a double strip 70 for binding the pans together. The outermost member of this double strip covers the inner member which is secured to each individual pan of the unit by rivets, lugs or spot welds, as before explained. The strip 75 may consist of two separate members, in which case the outer member has its upper longitudinal edge turned in over the adjacent top edge of the inner member. Or the strip may consist of a single piece doubled upon itself on a longitudinal line. In either 80 method the same beneficial result is accomplished, since the fastening means, depressions, and angled edges of the inner member are completely covered so that the disadvantages set forth above are done away with. 85 The strip of the present invention entails other desirable features which will appear in the course of the following description.

The second method of forming the strip, 90 that is by use of a single piece of material, is believed to be preferable and it is that method which is herein set forth. Referring to the drawings the metal pans 5 and 6 are shown as formed by the folding method before described, the said sides 7 having integral endwise extensions which are turned at right angles against the end portion 8, of the pans, to provide the end folds 9. The rolled edges 10 inclose the strengthening wire 95 11, said edges likewise serving to press the 100

end folds 9 against the end portion 8, as illustrated at 12 in Fig. 2. A spacer 13 is secured between each pair of pans in the unit, between the side edges thereof.

5 The strip 14 of the present invention is formed of suitable metal or band iron and has the inner member 15 and outer member 16. One of the strips 14 is positioned along each side of a unit of pans, that is, along the 10 aligned ends of a plurality of pans. The member 15 is herein shown as secured to the pans by means of lugs or ears 17, struck out from member 15. In Fig. 3 is shown a pair of such ears, the view showing that side of 15 member 15 which is placed against the pan ends. It is seen that the ears 17 may be inserted beneath the end folds 9, of each pan, at points adjacent the lower halves of the pans where folds 9 are more divergent. Ears 20 17 having been thus initially inserted, the strip 14 is moved upwardly, until its top edge is just beneath the edges 10 of the pans. Thereafter, ears 17 and member 15 are pressed toward one another to firmly grip folds 9 between them. Any desirable method of securing the strip 14 to the pans, may be used, such as by rivets extending through member 15 into the pan ends.

Outer member 16 consists of the upper longitudinal portion of strip 14, member 16 being bent down against the exterior side of member 15. Strip 14 is bent so as to present the bulbed or beaded edge 18 which extends outwardly from the pans somewhat farther than edges 10, thus protecting the latter from becoming dented and misshapen by contact with other objects. The lower edge 19 of member 16 extends below the adjacent edge of member 15, and is pressed inwardly 40 against the pans. At the upper corners of the two ends of strip 14 an extension 20 of member 16 is provided. After strip 14 is secured beneath edges 10, these extensions 20 are bent about the adjacent corners of the 45 end pans of the unit, after which an end strip 21 may be superimposed on extensions 20 and a rivet 24 or other means, utilized to secure both the extensions 20 and the end strips 21, to the sides of the end pans. It will be observed by reference to Fig. 1 that member 15 is cut vertically at its ends 22. The ends of strip 16 overlap ends 22, and edges 23 of strip 16 are bent against the pans to preclude the 50 entry of dirt, grease and the like. It is evident that strip 14 may be of any length so that any desired number of pans may be strapped together in this way.

55 Strip 14 greatly increases the strength and durability of a baking unit; its bulbed edge 60 acts as a bumper to protect the top edges of the pans, and its smooth outer surface collects no grease nor dirt and does not injure the hands and clothing of persons handling the 65 pans.

What is claimed is:

1. A connecting and re-enforcing strip for multiple baking pans comprising an inner and an outer member joined along their upper longitudinal edges by a bead, the inner 70 member being adapted for connection with the pans of the unit, and the lower edge of the outer member overlapping the lower edge of the inner member.

2. A means for connecting and re-enforcing the pans of a baking unit, said means comprising a metal strip bent longitudinally upon itself to provide two members, one member adapted to be secured to the ends of the pans, and the second member superimposed upon the first member and having its lower edge and its end edges overlapping the like edges of the first member, the upper joined edge of the two members being positioned adjacent the top edges of the pans and 85 extending outwardly beyond said edges.

3. A strip for connecting the pans of a baking unit and comprising a member adapted to be secured to the pans, and a covering member superimposed on and overlapping the edges of said first member for preventing the entry of dirt and the like between 90 said two members.

4. The combination with multiple baking 95 pans, of means for connecting and reenforcing the pans and comprising a strip member adapted to be secured to the pans, and a second strip member joined to the first member adjacent the upper longitudinal portion thereof, the second member covering the first member and having its lower edge overlapping the lower edge of the first member and pressed inwardly against the pans whereby to prevent the entry of dirt and the like between the strip members.

5. A pan-connecting means comprising a strip adapted for attachment to a plurality of pans, and a covering member adapted to be attached to said strip and to overlap the edges thereof.

6. A pan-connecting strip comprising an inner member adapted for attachment to a plurality of pans, and an outer member providing an unbroken outer surface and adapted to be attached to and to cover said inner member, the lower edge portion of the outer member being adapted to overlap and to be bent inwardly beneath the like portion of the inner member.

In testimony whereof, I have hereunto subscribed my name this 19th day of November, 1928.

FRED SCHULTZ.
